UNITED STATES PATENT OFFICE.

LEWIS A. MYERS, JR., OF NEWARK, NEW JERSEY.

DESIGN FOR A BELT.

SPECIFICATION forming part of Design No. 35,842, dated April 1, 1902.

Application filed February 10, 1902. Serial No. 93,381. Term of patent 3½ years.

To all whom it may concern:

Be it known that I, LEWIS A. MYERS, Jr., a citizen of the United States, residing at Newark, in the county of Essex, State of New Jersey, have invented and produced a new and original Design for a Belt, of which the following is a specification, reference being had to the accompanying drawings, forming part thereof.

10 The leading feature of my design for a belt is a body composed of longitudinally-extending bands and loops, the latter being elliptical, portions of the bands passing through the said loops and being gathered at the ends 15 of the latter and then expanded between said ends.

Figure 1 represents a rear elevation of a belt embodying my design. Fig. 2 represents a vertical section thereof on line xx , Fig. 1. 20 Fig. 3 represents a vertical section on line yy , Fig. 1.

In the drawings, A designates a belt, the

body of the same being composed of the longitudinally-extending bands B B', the central loops C, the side loops C', and the vertically-extending straps D D'. The bands B bisect said straps at said loops and pass partly through the latter, as at E. The central band B passes over the straps D', as at F, and between the members of the adjacent loops C'. 25 The loops are flattened and elliptical, and the portions of the bands that pass through the same are gathered and reduced at the ends of the loops and then expanded between said ends. 30

Having thus described my invention, what I claim as new, and desire to secure by Letters Patent, is—

The design for a belt substantially as shown and described.

LEWIS A. MYERS, JR.
